LIGHTING FIXTURE

Dirk G. Saaf, Chicago, Ill., assignor to Goodrich
Electric Company, Chicago, Ill., a corporation
of Illinois

Application August 6, 1936, Serial No. 94,493

5 Claims. (Cl. 240—103)

The invention relates generally to a lighting fixture and more particularly to a fixture of the reflector type especially adapted for use with bowl silvered lamps.

5 It is a general object of the invention to perfect a new and improved lighting fixture having a reflector which produces a high intensity of well diffused illumination, utilizes the full efficiency of a bowl silvered lamp, and is readily 10 manufactured and installed.

Another object is to provide a lighting fixture for use with bowl silvered lamps having a reflector shaped to produce a high degree of useful downward illumination and to deflect a portion of the light upwardly to increase the upward illumination.

Other objects and advantages will become apparent from the following detailed description taken in connection with the accompanying drawing, in which:

20 Fig. 1 is a diametrical sectional view of a fixture embodying the features of the invention.

Fig. 2 is a diametrical view of a modified form of the fixture shown in Fig. 1.

25 While the invention is susceptible of various modifications and alternative constructions, it is here shown and will hereinafter be described as embodied in a preferred form and one modification, but it is not intended that the invention 30 is to be limited thereby to the specific constructions disclosed, but it is intended to cover all modifications and alternative constructions falling within the spirit and scope of the invention as defined by the appended claims.

35 In the drawing, 5 designates a socket which preferably is of the vertically adjustable type, and 6 designates a lamp commonly known as a bowl silvered lamp. Such a lamp has on its lower or globe end a semi-spherical reflecting means 40 which reflects the light rays upwardly and prevents direct downward illumination. The reflecting means is formed by the application of suitable matter such as mercury or silver in the globe as a coating, or even by embedding the 45 same in the glass of the globe. Surrounding the socket 5 is a generally conical supporting hood 7 terminating in a threaded lower end 8. Supported from the hood 7 is a reflector generally designated 9. Both the hood and the reflector 50 are coated with fused white porcelain enamel.

The reflector is shaped to produce a high intensity of well diffused, downward illumination, and to that end comprises an annular top portion 10 which extends upwardly and inwardly from 55 its outer to its inner periphery and is slightly

curved to form a concave reflecting surface on the inner side thereof. Depending from the outer periphery of the top portion 10 is an annular outer skirt portion 11 extending downwardly and somewhat outwardly from its inner to its outer or free periphery. This skirt portion also is slightly curved so that the inner side thereof forms a second concave reflecting surface. An annular inner skirt portion 12 extends sharply inwardly and downwardly from the inner periphery of the top portion 10 to complete the reflector. This inner skirt portion is disposed to direct the light rays outwardly against the top and outer skirt portions to equalize the intensity of the light striking those portions of the reflector.

10 In the form of the invention shown in Fig. 1, the inner skirt portion 12 is formed as an integral part of the top portion 10 and curves sharply inwardly and downwardly to provide on its inner side a concave reflecting surface of a much smaller radius of curvature than either the top portion 10 or the outer skirt portion 11. The curvature preferably is such that a majority of the light rays striking the skirt portion 12 are 15 reflected against the top portion 10 from whence they are again reflected against the outer skirt portion 11 so as to be well diffused before being directed downwardly.

15 In order that a portion of the illumination may 20 be directed upwardly, the inner skirt portion 12 is formed with an aperture 13 large enough to permit the projection therethrough of a portion of the lamp 6 proper, and the reflector is spaced from the hood 7. Herein the reflector carries a 25 conical collar 14 having an upper threaded portion 15 adapted to be screwed into the threaded portion 8 of the hood 7. The collar 14 is secured to the reflector proper in spaced relation thereto by a plurality of legs 16 making a perforate member thereof. With this construction, light rays from the upper part of the lamp projecting through the aperture 13 in the inner flange 12 may pass through the space between the reflector and the collar 14 to illuminate the ceiling of the 30 room in which the fixture is mounted. Such upward illumination is increased by the shape of the inner skirt portion 12, the outer surface of which serves to reflect the light rays. The amount of upward illumination may be varied 35 by adjusting the socket 5 so that a greater or lesser portion of the lamp 6 projects through the aperture in the reflector, as shown in dotted outline in Fig. 1.

The vertically adjustable socket 5 serves the 40

additional purpose of properly positioning lamps of different size to utilize the full efficiency thereof. The threaded connection between the reflector and the hood 7 initially facilitates installation and wiring and subsequently facilitates removal for cleaning and servicing.

In the modified form shown in Fig. 2, the inner skirt portion 12 is formed of a separate inverted conical member secured to the top portion 10 by screws 17, while a collar 14' having a threaded upper end portion 15' for engagement with the threaded portion 8 of the hood 7 is formed as an integral part of the reflector. In this form of the invention, the collar 14' is an imperforate member preventing any upward illumination.

I claim as my invention:

1. A lighting fixture comprising a lamp socket, a supporting hood surrounding said socket having a threaded lower end, and a reflector adapted to be secured to said hood to be supported thereby comprising a collar having a threaded upper end portion for engagement with the threaded portion of said hood, and annular top portion extending upwardly and inwardly from its outer to its inner periphery and slightly curved to form a concave reflecting surface on the inner side thereof, an annular depending outer skirt portion extending downwardly and outwardly from its inner to its outer periphery and also slightly curved to form a second concave reflecting surface, an annular inner skirt portion extending sharply inwardly and downwardly from the inner periphery of the top portion to provide inner and outer reflecting surfaces and having a central aperture permitting insertion therethrough of a portion of a lamp to be supported in said lamp socket, and a plurality of legs securing said collar to the reflector proper in spaced relationship to permit upward illumination by the fixture.

2. In a lighting fixture a reflector having an inner annular skirt portion provided with inner and outer reflecting surfaces and having a central aperture, said portion extending inwardly and downwardly to surround in spaced relation the portion of a lamp projecting through the central aperture in said annular skirt portion, and

perforate supporting means secured at the top of said reflector to permit upward illumination thereby.

3. In a lighting fixture, a reflector comprising an annular top portion extending inwardly and upwardly from its outer to its inner periphery and curved slightly to form a concave reflecting surface on its inner side, a depending annular outer skirt portion extending downwardly and outwardly from its inner to its outer periphery to form a second concave continuous reflecting surface on its inner side, and an inner annular skirt portion curving continuously and sharply inwardly and downwardly from the inner periphery of said top portion to form a third continuous reflecting surface, the radius of curvature of which is substantially less than that of the outer surfaces, being operable to reflect outwardly to the other concave reflecting surfaces, said inner skirt portion having a central aperture for the protection therethrough of a portion of a lamp.

4. In a lighting fixture, a reflector comprising an annular top portion extending inwardly and upwardly from its outer to its inner periphery and curved slightly to form a concave reflecting surface on its inner side, a depending annular outer skirt portion extending downwardly and outwardly from its inner to its outer periphery and also being slightly curved to form a second concave reflecting surface on its inner side, and an inverted conical member forming an annular inner skirt portion extending inwardly and downwardly from the inner periphery of said top portion and facing so as to reflect light to the other concave reflecting surfaces.

5. In combination with a lamp and socket therefor, a reflector supported in spaced relation to the lamp comprising an annular skirt portion of sheet-like structure surrounding the lamp having exposed reflecting surfaces on both sides thereof and curved to present both reflecting surfaces to the lamp for reflecting illumination from one portion of said lamp outwardly in one direction and from another portion of said lamp outwardly in a second direction.

DIRK G. SAAF.
